CLAIM

The ornamental design for a seat, as shown and described.

DESCRIPTION

FIG. 1 is a front perspective view of the seat in the form of a love seat embodying our new design;
FIG. 2 is a front elevational view of our new design;
FIG. 3 is a top plan view of the design;
FIG. 4 is a rear elevation view of the design;
FIG. 5 is a front perspective view of the seat in the form of a sofa showing a second embodiment of our new design, the sole difference of which is substantially a matter of length; and,
FIG. 6 is a side elevational view of the various embodiments of our new design, the opposite side of each embodiment being substantially a mirror image thereof (with or without the handle shown in phantom).
The broken line showing of a handle is for environmental purposes only and forms no part of the claimed design.
